Primary Examiner—Donald P. Walsh*Assistant Examiner*—Jeffrey Asch*Attorney, Agent, or Firm*—Knobbe, Martens, Olson & Bear[57] **CLAIM**

The ornamental design of a collapsible workstand, as shown and described.

DESCRIPTION

FIG. 1 is a perspective view of a collapsible workstand showing my new design;

FIG. 2 is a perspective view of the article in a collapsed condition;

FIG. 3 is a side elevational view of the article in an unfolded condition;

FIG. 4 is a top plan view;

FIG. 5 is a side elevational view showing the opposite side shown in FIG. 3;

FIG. 6 is a bottom plan view; and,

FIG. 7 is a bottom plan view thereof showing the article in partially collapsed condition.

FIGS. 3-7 have been shown on a reduced scale with respect to FIG. 1.
